FORCED DRAFT DEVICE FOR STEAM
BOILERSPercy Harold Routledge, Mission, British
Columbia, Canada

Application March 27, 1941, Serial No. 385,562

3 Claims. (Cl. 230—100)

My invention relates to improvements in forced draft devices for steam boilers which are particularly adapted for use in locomotives. The objects of the invention are to utilize the exhaust steam from reciprocating engines to provide a substantially constant and steady flow of gases from the fire box of the engine boiler through the smoke stack, also to provide for a general reduction of the back pressure on the engine, and to provide means for adjusting the operative parts to obtain efficient service at all stages of engine load from starting up to normal running conditions.

The invention consists essentially of a Venturi ejector structure including a cone for confining and directing the exhaust steam through the Venturi throat and an inner cone concentric therewith, as will be more fully described in the following specification and shown in the accompanying drawing, in which:

Fig. 1 is a plan view of the smoke box of a locomotive showing the ejector as taken on the line 1—1 of Figure 2.

Fig. 2 is a front elevational view of the invention.

Fig. 3 is a transverse sectional view of the ejector cones and adjusting means therefor.

Figs. 4 and 5 are fractionated sectional views showing different positions of adjustment of the inner cone.

In the drawing like characters of reference indicate corresponding parts in each figure.

The numeral 1 indicates generally a locomotive frame upon which a saddle 2 is mounted to support the front end or smoke box 3 of the locomotive boiler. Engine castings 4 are secured to the frame 1 and extend upwards to connect directly to the lower peripheral wall of the smoke box 3. Each engine casting includes a working cylinder 5 and a piston valve cylinder 6 and exhaust passages 7 are formed in the castings as indicated in dotted line in Figure 2 which communicate with opposite ends of the piston valve cylinders. The several exhaust passages 7 lead respectively to flanges 10, 11, 12 and 13, the flanges 10 and 11 communicate respectively with the rear and forward ends of the piston valve cylinder 6 of the "left" engine and the flanges 12 and 13 communicate respectively with the forward and rear end of the piston valve cylinder 6 of the "right" engine of the locomotive. To each of the flanges 10, 11, 12 and 13, pipes 14, 15, 16 and 17 are connected, which communicate with the lower peripheral wall 18 of a cone 19 tangentially.

The upper end of the cone 19 terminates in

a Venturi throat or jet 22 having a slight flare 23 at its tip. The cone 19 is enclosed with a bottom wall 24 having a bearing 25 in which a vertical shaft 26 is journaled. The shaft is threaded at its upper end as at 27 and engages a cross member 28 of an inner cone 29 which is telescopically mounted in a collar 30 carried from the bottom wall 24. The inner cone 29 is provided with guide pins 31 which project through the bottom wall to prevent said cone from turning with the shaft 26. The shaft 26 is rotated by mitre gears 33 from a horizontal shaft 34 which is operated from the cab of the locomotive by any suitable means. The inner cone 29 is fitted at its apex with a ball 36 which is adapted, when the cone is in its lowermost position as shown in Figure 4, to define a very narrow annular passage through the throat 22.

Mounted in the wall 33 of the smoke box 3 is a smoke stack 39 formed of two opposed frustoconical portions 40 and 41 with throat or point of greatest constriction at their intersection as at 42. The length of the lower portion 40 and the disposition of the throat 42 with respect to the jet 22 of the cone 19 is designed to provide for the proper filling of the stack 39 with smoke entering the stack from the interspace 44 between the top of the cone 19 and the base of the stack.

The operation of the device is as follows:

When about to start the locomotive the inner cone 29 is lowered until the horizontal axis of the ball 36 is in a plane coincident to the top of the cone 19 and the inner cone wall is at its greatest distance from the inner surfaces of the cone 19, thus producing a conical steam passage 45 therebetween of maximum width. Each engine cylinder exhausts its steam into the conical steam passage 45 and flows therewith spirally towards the jet. The resulting bursts of exhaust steam following each other at close intervals, set up a steam flow which becomes substantially continuous before it passes through the jet and also sets up a flow of progressively increasing velocity due to the decrease of diameter of the annular passage 45 towards the top of the cones. As the steam reaches the jet 22 its velocity is high and due to the narrowing down of the passage between the jet 22 and the ball 36 its flow is still further increased to a point where there is substantially no interval between successive exhausts, consequently the steam flowing at high and constant speed serves to provide a consistently high vacuum in the smoke box and at the base of the stack. This high speed steam flow traveling spirally upwards becomes constant at

the point of discharge from the cone and due to momentum lessens the pressure on each of the exhaust pipes 14, 15, 16 and 17 at the time when their respective exhaust valves are closed, hence the initial back pressure against the pistons of the engine is materially reduced and greater power is obtained from said engines for a given quantity of steam. As the inertia of the load is being overcome and momentum is increased to enable the cut off to take place earlier a lesser volume of steam will be exhausted per stroke, though the number of exhausts will be increased per unit of time, the volume of steam exhausted however being less than when starting it is desirable to raise the cone accordingly so as to reduce the width of the passage 45 while projecting the ball 36 beyond the jet 22 as shown in Figure 5, when the ball will serve to spread the steam as it passes through the jet to fill the stack 39 and maintain the same negative pressure within the smoke box 3.

What I claim as my invention is:

1. An ejector comprising a circular chamber having a peripheral wall and a top opening and a tubular member concentric with and spaced above the top opening, exhaust pipe connections communicating with the chamber through said peripheral wall, a vertically movable member between the exhaust pipe connections and the top opening defining a passage leading to said opening, said member having an enlargement adapted to reduce the effective cross sectional area of the passage through the top opening when said mem-

ber is in its lowermost position and to project through the opening to increase the effective cross sectional area of the opening when the member is in raised position.

- 5 2. An ejector comprising a chamber having a base and a frustoconical wall terminating in a top opening and a tubular member concentric with and spaced above the top opening, a vertically movable cone within the chamber having an enlargement supported above its apex, exhaust pipe connections communicating with the base of the chamber, said enlargement being so disposed above the cone as to reduce the effective cross area of the top opening when the cone is in its lowermost position and to increase the effective cross sectional area of the top opening as the cone is raised within the chamber.
- 10 3. An ejector comprising a chamber having a base and a frustoconical wall terminating in a top opening and a tubular member concentric with and spaced above the top opening, a vertically movable cone within the chamber having a spherical enlargement supported above its apex, exhaust pipe connections communicating with the base of the chamber, said enlargement being so disposed with respect to the top opening as to provide a narrow annular passage through said opening when the cone is in its lowermost position and to increase the width of the annular passage as the cone and said enlargement are raised.
- 20 25 30

PERCY HAROLD ROUTLEDGE.
